W. M. GENTLE.

CARBURETER.

APPLICATION FILED MAR. 9, 1910.

1,000,398.

Patented Aug. 15, 1911.

UNITED STATES PATENT OFFICE.

WILLIAM M. GENTLE, OF GREENWOOD, INDIANA.

CARBURETER.

1,000,398.

Specification of Letters Patent. Patented Aug. 15, 1911.

Application filed March 9, 1910. Serial No. 548,188.

To all whom it may concern:

Be it known that I, WILLIAM M. GENTLE, of Greenwood, county of Johnson, and State of Indiana, have invented a certain new and useful Carbureter; and I do hereby declare that the following is a full, clear, and exact description thereof, reference being had to the accompanying drawings.

The object of this invention is to improve the construction and operation of carbureters.

A feature of the invention is the elimination of the float common in such devices. This renders it possible to omit the large fuel chamber and the fuel cannot "slop" out and the device does not need to be maintained in any particular position as is true of carbureter containing float chambers.

Another feature consists in utilizing the intake of air under the action of the engine for controlling the supply of fuel to the carbureter as well as its access to the nozzle and the discharge of fuel from the nozzle. This dispenses with the ordinary needle valve or any other like valve for controlling the fuel supply. It is accomplished by mounting the air valve on a movable nozzle with a hollow nozzle stem having a port adapted to register with the fuel supply passageway for additional supplies of fuel at times particularly during high speed of the engine. At other times the supply of fuel to the nozzle stem is cut off but said nozzle stem always carries a limited quantity of fuel.

Another feature consists in the combination of a movable nozzle or fuel supply and a mixing chamber into which the nozzle is adapted to move during high speed of the engine, and, as the nozzle moves farther into the mixing chamber it is subjected more and more to the action of the air current through the mixing chamber wherein an increased quantity of fuel is drawn through the nozzle.

The foregoing and other features of this invention will be understood from the accompanying drawings and the following description and claims.

In the drawings Figure 1 is a central vertical section through the device with the valves in their idle position. Fig. 2 is the same as Fig. 1, with the valves actuated. Fig. 3 is a cross section on the line 3-3 of Fig. 1. Fig. 4 is a section on the line 4-4 of Fig. 2 and Fig. 5 is a section on the line 5-5 of Fig. 3.

In detail I provide an air chamber 10,

which consists of the two semi-spherical parts 11 and 12 and a mixing chamber 13. The carbureter has a bottom air inlet 14 which is normally closed by the valve 15. 60 This valve is secured to the valve stem 16 which extends upwardly through the frame 17 which is integral with the wall of the part 12 of the air chamber. The frame 17 has upper and lower rounded extensions 18 65 which are threaded and ground to receive the packing nuts 19. The stem 16 and the passageway through the frame 17 have finished faces and are made to fit the stem tight. The upper part of the stem 16 is tubular and the end threaded at the upper end to receive the spraying nozzle 20. This nozzle has a fine outlet 21, which opens into the mixing chamber 13 of the carbureter and there may be a plurality of openings. 75

The tubular part of the stem 16 forms a chamber 22 in which there is always a limited amount of fuel. A port 23 in said stem is adapted to bring the chamber 22 in communication with the fuel passageway 24. 80 This passageway extends around the stem 16 so as to permit a free inflow of fuel when the ports are in communication. The fuel outlet 21 in the nozzle 20 may vary in size to suit the density of the fuel. The passageway 24 is connected to a fuel tank by some suitable piping means and it is understood that the tank will be somewhat higher than the carbureter so that a slight pressure will cause the fuel to pass freely through 90 the pipe. As seen in Fig. 4 the pipe 25 is provided with a valve 26 which is adapted to cut off the supply of fuel to the carbureter when not in use. As seen in Fig. 1, the valve 15 and the port 23 are held normally 95 closed by the action of the spring 27 and, as seen in Fig. 2, they are opened by the suction of the engine with which the carbureter is associated. The upper port 13 of the carbureter is turned at a right angle and near 100 the center there is located a valve 28 which is secured at the lower edge to the rod 29 which has bearings in the side wall 7 of the tube 13. As seen in Fig. 3, the valve 28 is held normally closed by a spiral spring 30, 105 one end of which is secured in the rod 29 and the other to the side wall of the tube 13. On the other end of the rod 29 there is secured an arm 31 which is adapted to engage the stop lever 32. The lever 32 is loosely 110 mounted on the rod 29 and is operated by means, not here shown. As seen in the

drawings the valve 28 is throttled by the operation of the lever 32, that is, the valve 28 is free to move by the suction of the engine till the arm 31 engages the lever 32. 5 Then the opening of the valve will be stopped. On the underside of the outer end of the part 13 there is a valve 33 pivoted at 34 which is adapted to close the port 35. This valve is held normally closed by a flat 10 spring 36 which is secured to the boss 37 on the end of the tube 13.

The object of the valve 33 is to permit the back fire or premature explosion for the engine to have free access to the outer air and 15 not to pass through the carbureter. As seen in the drawings a back fire would assist in closing the valve 28 and cause it to open freely the valve 33, whereby the carbureter would not be damaged. In the upper end 20 of the port 12 there is an inwardly curved baffle plate 37 which assists in causing the inrushing air to concentrate around the spray nozzle 20, as seen in Fig. 2. This plate is cut away at 38 so as to fit around 25 the boss 17. It is held in place by the screws 39 passing through the vertical slots 40 and by the means first described is vertically adjustable. As seen in the drawings there is a channel flange 41 cast integral 30 with the frame 17 which is adapted to catch the excess or overflow of fuel. In Fig. 2 a means is provided for conveying the excess fuel from the channel 41 to some suitable receptacle not here shown. A pipe 42 leads 35 from the channel 41 to a valve 43. This valve is normally held open by the spring 44 but is closed by the suction of the engine. A pipe 45 connects the valve with some suitable receptacle. The construction shown in 40 Fig. 2 is for use where the nature of the fuel would be light and the overflow greater than where the fuel is heavy. With fuel of medium density the construction shown in Fig. 1 is desirable. The channel 41, is eliminated and the overflow of fuel is caught by 45 the valve 15 which is pan-shaped. This overflow evaporates in the pan 15 and is taken up by suction from the engine by the pan as seen in the drawings. The parts 11 and 12 are bell-shaped to form an air evaporating chamber for the overflow of fuel. As both ends of the carbureter are securely closed it will be seen that the chamber will 50 always contain a charge of explosive gas which feature will be of considerable advantage upon starting the engine. It will also be seen from the drawings that the valve 15 must be raised till the port 23 comes into 55 communication with the passageway 24 before out side air is admitted to the carbureter. This is due to the deep seat of the valve opening 14. Therefore, before the outside air passes into the carbureter, the pressure from the fuel tank through pipe 60 25, passageway 24, port 23, and chamber 22

forces the fuel up and out of the spray nozzle 20.

In operation the suction from the engine first opens the valves 28 and acts upon the spray nozzle slightly before lifting the 70 valve 15. As the valve 15 is lifted, the spray nozzle is also lifted so as to bring it nearest to the greatest condensation of the inrushing air.

What I claim as my invention and desire 75 to secure by Letters Patent is:

1. A carbureter including a chamber with an air inlet, a valve for closing it, a mixing chamber through which the air passes, a fuel nozzle movable into said mixing chamber by the movement of the valve controlling the intake of air, and means tending to close said valve and move said nozzle in a direction away from said mixing chamber and operating to permit the opening of the valve 85 and nozzle to an extent proportional to the strength of the air blast.

2. A carbureter including a chamber with an air inlet, a valve for closing it, a mixing chamber through which the air passes, a fuel nozzle movable into said mixing chamber by the movement of the valve controlling the intake of air, and a spring tending to close 90 said valve and move said nozzle in a direction away from said mixing chamber.

3. A carbureter including an air chamber with an air inlet, a valve for closing the air inlet, a mixing chamber through which the air passes, a fuel nozzle movable into said mixing chamber and carrying said valve so 100 as to be moved by the intake of air, and a spring surrounding said nozzle which tends to close said valve and move the nozzle in a direction away from said fuel chamber.

4. A carbureter including a casing having an air inlet and mixing chamber, a valve for closing said air inlet, a nozzle which is movable under the influence of the air intake acting on said valve and having a fuel chamber with a lateral inlet port, and a fuel 110 supply passageway leading to said nozzle and adapted to register with the port thereon only when the nozzle is actuated.

5. A carbureter including a casing having an air inlet and mixing chamber, a valve for closing said air inlet, a nozzle which is movable under the influence of the air intake acting on said valve and having a fuel chamber with a lateral inlet port, a fuel supply passageway leading to said nozzle and adapted to register with the port therein only when the nozzle is actuated, and a spring for holding said nozzle with the port out of registry for closing said passageway.

6. A carbureter including a mixing chamber through which the air is adapted to pass, a fuel nozzle movable by the intake of air farther into said mixing chamber in proportion to the intake of air, whereby the quantity of fuel drawn through the nozzle will 130

be in proportion to the air that passes through said chamber, and an adjustable plate for controlling the course of the air that passes the outlet of said nozzle.

- 5 7. A carbureter including a chamber provided with an air inlet, a valve for controlling said inlet and movable under the influence of the intake of air, a stem for said valve having a fuel chamber therein with
10 a port thereto, a nozzle forming a part of said valve stem and in communication with said chamber, and a fuel passageway adjacent the portion of the valve stem containing the port and normally out of registry
15 with said port so that when the valve is moved said port will be moved into registry with the fuel supply passageway.

8. A carbureter including a chamber pro-

vided with an air inlet, a valve for controlling the influence of the intake of air, a 20 stem connected with said valve and having a fuel chamber therein with a port there-
to, a nozzle forming a part of the valve stem and in communication with said fuel chamber, a fuel supply passageway adapted 25 to register with the port in said valve stem when the valve is actuated, a fuel overflow receptacle surrounding said valve stem, and means for draining said overflow receptacle.

In witness whereof, I have hereunto 30 affixed my signature in the presence of the witnesses herein named.

WILLIAM M. GENTLE.
